BUTTON ATTACHING TOOL WITH FEED
CHANNEL IN BASE

Newton E. Lyon, Denver, Colo.

Application February 25, 1948, Serial No. 10,837

1 Claim. (Cl. 218—21)

1

This invention relates to an improved clothing button and to a device for attaching the improved buttons to clothing, and has for its principal object the provision of a button and means for attaching the button which can be quickly and easily used by anyone; which will eliminate all the usual sewing operations; and which will securely attach the button against loss without damage to the garment.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side elevation of the improved button-attaching device;

Figs. 2 and 3 are cross-sections therethrough, taken on the lines 2—2 and 3—3, Fig. 1, respectively;

Fig. 4 is an enlarged cross-section through the improved button, illustrating it in the attached condition;

Fig. 5 is an enlarged, detail cross-section, taken on the line 5—5, Fig. 1;

Fig. 6 illustrates a stem employed in attaching the improved button;

Fig. 7 is a plan view of the button of Fig. 4; and

Fig. 8 is an enlarged cross-section through an alternate form of button.

The improved clothing button comprises a button 10, preferably formed of relatively hard, durable plastic and provided with a spacing flange 11 on its bottom side. The back of the button has a central opening for receiving an attaching stem 12, as shown in Fig. 6.

The stem consists of a hollow, tubular member having splits 13 extending inward from the end and provided with a relatively flat, thin head 14.

The interior of the button 10 is hollow and is provided with a spreading point 15 opposite the entrance of the stem 12 so that when the stem 12 is forced into the button, the point 15 will enter the hollow, split extremity of the stem and spread it outwardly into the hollow button, as shown in Fig. 4.

The stem may be forced into the button in any desired manner. In fact, the buttons can be attached by hand by simply squeezing the stem 12

2

into the button 10 with a plier-like tool or driving it therein with a driving instrument. A special tool, however, is provided to facilitate the attachment of the improved buttons. This tool is illustrated in Figs. 1, 2, and 3 and comprises a sheet metal housing 16 having a hollow, rectangular, elongated, tubular base portion 17 formed therewith or permanently attached thereon.

10 A gripping handle 18 is pivoted upon a suitable pivot pin 19 between the two sides of the housing 16. The handle is provided with a lifting arm 20 extending forwardly from the pivot pin 19. A rocking link 21 is mounted upon a pivot pin 22 between the sides of the housing 16 forwardly of the lever 20. The link 21 carries a cross pin 23 which rides in a slot 24 in the extremity of the lever 20.

15 The forward extremity of the link 21 enters 20 a plunger 25 which is vertically slidable in the housing 16. A pin 26 passes through the plunger and through a terminal slot 27 in the end of the link 21.

25 A spring 28 surrounds the pivot pin 19 and is secured at one extremity to the housing 16 and at the other extremity to the lever 20, and acts to constantly urge the handle 18 away from the rearwardly projecting portion of the base 17.

30 It can be readily seen that if the handle 18 is 30 squeezed toward the base, it will cause the plunger 25 to move toward the base with increased leverage. The lower extremity of the plunger is provided with a pressure plate 35. The hollow interior of the base 17 is designed to receive a 35 row of the stems 12 of Fig. 6 so that they may move successively forward to a position beneath the pressure plate 35.

The stems may be forced forwardly in the base 17 by means of a finger button 29 having a stem 40 30 which passes through a longitudinally extending slot in the bottom of the base 17. The stem terminates inside the base 17 in a pusher block 31 which bears against the rearmost head 14 in the row. A spring 32 is inset in the finger button 45 29 and constantly urges a friction washer 33 against the bottom of the base 17 to hold the block 31 in any desired position therein.

50 The bottom of the base is depressed, as shown at 34, so that the pusher block 31 may be moved into the depression to allow additional stems to be placed in the base. It is preferred to form a socket 36 in the center of the pressure plate 35 for the initial reception of the stem 12.

55 In use, the foremost stem is placed beneath the button position on the fabric, indicated at

37, Fig. 4, and the handle 18 is depressed. This forces the stem through the fabric into the socket 36. The tool is then opened and one of the buttons 10 is placed over the end of the protruding stem. The tool is again closed to force the button 10 down on the stem. This forces the split end of the stem against the spreading point 15 to spread the stem outwardly into the hollow interior of the button 10, as shown in Fig. 4. The button is now permanently and securely attached to the fabric 37.

In Fig. 8 an alternate form of the button is illustrated, comprising a circular metal insert 38 imbedded in plastic 39, the latter forming the design of the button per se. The insert 38 is formed in a flat cup-like shape having an open side for receiving the extremity of the shank 12 and an inwardly extending rounded bulge 40 for spreading the extremity of the shank 12 similarly to the action of the spreading point 15.

With a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

A button attaching tool comprising an elongated base open at front and rear ends and having a bottom and a top wall and side walls, the bottom being formed with a longitudinally extending slot and having its front end portion projecting forwardly beyond the side walls and the top wall and constituting a fastener-receiving platform, a pusher in said base resting upon the bottom and having a stem passing through the slot and a finger-engaging member at its lower end, the rear end portion of the bottom

being offset downwardly and thereby forming a depressed seat adapted to receive the pusher and dispose the pusher in a countersunk position allowing movement of fasteners into the base through the rear end thereof and forwardly across the pusher to a position in front of the pusher, a hollow housing extending upwardly from the base and forwardly in upwardly spaced relation to the top wall and having its front end portion disposed over the platform, a plunger slidably vertically through the front end portion of said housing and provided with a button-engaging head at its lower end disposed directly over the platform, a handle over the rear portion of said base having its forward portion extending into the rear end portion of the housing and pivotally mounted, an arm extending forwardly from the front end of the handle at an upward incline in the housing, and a link extending longitudinally in the forward portion of the housing between the plunger and the arm and pivotally mounted for vertical rocking movement and having its front and rear ends pivotally and slidably connected with the plunger and the front end of the arm.
